[57] CLAIM

The ornamental design for a dust mop frame, as shown
and described.

DESCRIPTION

FIG. 1 is a top, front and left side perspective view of a
dust mop frame showing my new design;FIG. 2 is a left side elevational view thereof, the right
side being a mirror image;

FIG. 3 is a rear elevational view thereof;

FIG. 4 is a front elevational view thereof;

FIG. 5 is a top plan view thereof; and,

FIG. 6 is a bottom plan view thereof.

The mop yarn shown in broken lines in the drawings is
for illustrative purposes only and forms no part of the
claimed design.FIG. 1

FIG. 2

FIG. 3

FIG. 4
